Primary Examiner — Sandra S Snapp*Assistant Examiner* — Ieisha N Price(74) *Attorney, Agent, or Firm* — Tucker Ellis LLP(57) **CLAIM**

The ornamental design for a sleeve for handle puller, as shown and described.

DESCRIPTION

FIG. 1 is a perspective view of a sleeve for handle puller showing the design;

FIG. 2 is a top view thereof;

FIG. 3 is a bottom view thereof;

FIG. 4 is a right side view thereof; and,

FIG. 5 is a front view thereof.

The broken lines in the drawings illustrate portions of the sleeve for handle puller which form no part of the claimed design.
